ATTY

UNITED STATES PATENT OFFICE.

ABRAHAM WAISMAN, OF ST. LOUIS, MISSOURI.

GARMENT RETAINER.

Application filed February 1, 1926. Serial No. 85,140.

My invention relates to improvements in garment retainers, and has for its primary object a device constructed of rubber which is designed to be slipped over existing suspender buttons sewed on the inside of trousers and contact with the shirt so as to prevent the creeping up of the shirt due to the bending of the body. It frequently happens that without my retainer the shirt will 5 continue to creep up until the lower edge thereof finally hangs over the trousers, thus embarrassing the wearer to a great extent.

A further object is to construct a garment retainer of elastic material preferably rubber which can be easily applied to existing buttons on the inside of trousers or skirts and to frictionally engage with a waist or shirt and prevent the same from slipping up.

20 My device is designed for use in connection with any ordinary button which can be readily sewed to the garment and therefore does not require a special stud or button to secure it in position.

25 In the drawings:

Fig. 1 is a face view of my device;

Fig. 2 is a central cross section of the same;

30 Fig. 3 is a modified form of construction in which the edge is scalloped;

Fig. 4 is a face view of a modified form of construction;

Fig. 5 is a side elevation of the same; and

35 Fig. 6 is an enlarged sectional view of my device showing the same in use.

In carrying out my invention I employ a concavo-convex member 7. This member is thinnest at its center and gradually increases in thickness toward its edge as illustrated in Fig. 2 thereby forming a relatively thin wall 8 and a heavy edge 9 which is arranged to lie in a plane at right angles to the axis of the member 7. The member 7 is provided with a perforation 10 which is

40 preferably concentric to the edge 9 in the event that a circular member is used but should the shape of the member be changed, the opening 10 is designed to be substantially in the center thereof. The member 7 is formed of elastic material, preferably live rubber so that the opening 10 can be stretched over a button 11 as illustrated in Fig. 6 and fit snugly around the threads which secure the button while the edge 9 45 will ordinarily project beyond the button so that when the device is in use the pressure

of the edge 9 against the shirt 12 will cause the retainer to slightly bulge away from the rear surface of the button as illustrated in Fig. 6, but still permit frictional engagement between the retainer and the shirt so that the shirt will not readily pull up when the body of the wearer is bent.

The button 11 is designed to be secured to the inside and adjacent the top edge of 60 a pair of trousers or skirt 13. My device can be readily attached and removed from the button by reason of the elasticity of the material and by my construction no special form of button is required, as my device 65 is intended to be applied especially to the existing suspender buttons which are now secured on the inside of the waist band of trousers and to frictionally engage a shirt and retain it within the trousers without 70 the consequent bulging now present, making a shirt resemble a blouse, and also with the consequent attending embarrassing position of having the shirt-tail creep out over the top of the trousers and hang down on the 75 outside thereof. The retainer being made of live rubber, it does not create any great pressure against the body of the wearer on account of its resiliency but still at the same time creates sufficient friction or gripping 80 action to prevent the creeping of the shirt.

85 My device is also readily removable so that it can be shifted from one garment to another without the necessity of removing any of the buttons which retain it in position.

90 It is to be understood, of course, that in addition to the ordinary suspender buttons sewed on the inside of trousers, additional buttons may be interposed, it being my intention to have at least six of such buttons secured to the garment although the number may be increased or diminished, if desired, without departing from the spirit of my 95 invention.

100 It will be further noted that my device does not necessitate the use of separate buttons which must be removed every time the retainer is changed from one garment to another nor does it require any special 105 form of belt or other retaining device to hold them in position because, as before stated, any ordinary button which can be attached permanently to the garment, either by means of stitching or otherwise, is sufficient for the attachment of my retainer.

110 The essential feature of my device is a

concavo-convex or cup-shaped member which gradually increases in thickness from the center to the edge so that a minimum amount of material is present at the center 5 whereas a maximum amount of surface is exposed to frictionally engage a garment and prevent its creeping.

If found desirable the face 9 may be provided with radially extending ribs or corrugations so that more friction will be created than by merely having a smooth surface. I do not, however, desire this to be understood that a smooth surface as illustrated in Figs. 1 and 2 will not function 15 properly as a device made in this manner will accomplish my purpose but with the corrugations or ribs the gripping tendency of the retainer is enhanced.

As previously pointed out, it will be observed 20 that my garment retainer has its thinnest or most elastic portion around the opening 10, and the retainer gradually increases in thickness to the edge. By having the portion surrounding the opening 10 relatively thin, it can be more readily stretched, applied to and removed from a button. Then again as illustrated in Fig. 6 when the device is in use, this portion of 25 the retainer flattens out without necessarily displacing the edge 9 resting against the garment. In other words, by distorting or flattening out the portion of the retainer around the opening 10, the position of the edge 9 is practically undisturbed, that is to say it will lie flat against the garment where-

as this would not be the case if the retainer was of uniform thickness and flexibility throughout.

Having fully described my invention, what I claim is:—

1. A garment retainer formed of a single circular piece of elastic material and being concavo convex in cross section and provided with an opening, the material surrounding said opening being thinner, more 45 flexible and elastic than the remaining portion of the retainer whereby this portion of the retainer may flatten under pressure without distorting the remaining portion of the retainer. 50

2. A garment retainer formed of a single circular piece of rubber and being concavo convex in cross section and provided with a central opening and a flat circular edge lying in a plane at right angles to the axis of the 55 retainer, said retainer being of gradually increasing thickness from said opening to said edge.

3. A garment retainer formed of a single circular piece of rubber and being concavo 60 convex in cross section and provided with a corrugated edge and with a central opening, said retainer being of gradually increasing thickness from said opening to said edge whereby the material surrounding the opening may flatten without disturbing the position of the edge. 65

In testimony whereof I have affixed my signature.

ABRAHAM WAISMAN.
